UNITED STATES PATENT OFFICE.

JOSEPH ROBERT GIBSON, OF OUTREMONT, QUEBEC, CANADA.

SAFETY-LOCK FOR WATER-GAGE MOUNTINGS.

1 087,008.

Specification of Letters Patent.

Patented Feb. 10, 1914.

Application filed July 17, 1913. Serial No. 779,653.

To all whom it may concern:

Be it known that I, JOSEPH ROBERT GIBSON, a subject of the King of Great Britain, and resident of 747 Durocher street, in the 5 town of Outremont, Province of Quebec, Canada, have invented certain new and useful Improvements in Safety-Locks for Water-Gage Mountings; and I do hereby declare that the following is a full, clear, and 10 exact description of the same.

The invention relates to improvements in safety locks for water gage mountings as described in the present specification and illustrated in the accompanying drawings 15 that form part of the same.

The invention consists essentially of the rigid connection arranged between the valve handles.

The objects of the invention are to 20 devise a means of avoiding serious accidents to steam boilers and even to life and property resulting from the inaccurate indications by water gages due to the inopportune closing of a valve, and to provide a simple, 25 cheap and efficient device for the said purpose.

In the drawings, Figure 1 is a perspective view of a water gage and mounting and the locking device secured thereto. Fig. 2 is a 30 perspective detail of a locking nut. Fig. 3 is a perspective detail of the rod and fixed nut.

Like numerals of reference indicate corresponding parts in each figure.

Referring to the drawings, 1 is the gage 35 glass communicating with the boiler through the valve casings 2 and 3.

4 and 5 are valve stems projecting into the casings 2 and 3 respectively for controlling the communication of the gage 40 glass with the boiler.

6 and 7 are lever handles rigidly secured in the center thereof to the outer ends of the stems 4 and 5 respectively, one section 45 of each of said handles being circular in cross section and the other square as customary.

8 is a rod having the handle 9 at the lower end thereof and threaded on the upper portion thereof.

10 is a nut rigidly secured on the lower

end of the rod 8 adjacent to the handle 9 and having the lug extension 11 projecting laterally therefrom, said lug having a vertical orifice therethrough corresponding to 55 the circular section of the handle 6 and adapted to be mounted on said section of said handle 6.

12 is a nut having an internal thread corresponding to the upper threaded portion 60 of the rod 8 and turning thereon, said nut having a lug 13 projecting laterally therefrom with a vertical orifice 14 therethrough corresponding to the circular section of the handle 7 and adapted to be mounted 65 thereon.

In the use of this device the adjustable nut 12 is screwed to the proper place on the rod corresponding to the distance between the handles 6 and 7 and the two lugs mounted on the circular sections of the handles. This is done when the valves are open and the water running into the water gage glass, therefore the valves must remain open until the locking rod is removed. 70

This application has been limited to water gage mountings but it must be understood there may be other applications of the invention and it may be done in different ways, the chief feature being that the handles of valve stems are rigidly connected 80 and held in one position.

What I claim is:-

1. In a safety lock for water gage mountings, a rod, lugs extending laterally from 85 said rod having vertical orifices therethrough, and valve handles having projecting pieces extending into said vertical orifices.

2. In a safety lock for water gage mountings, a rod, a lug fixedly secured to said rod at the lower end thereof, a lug adjustably secured to said rod at the upper end thereof, said lugs having vertical orifices therethrough, and lever handles adapted to operate valves, each having one section thereof extending upwardly through a lug. 95

3. In a device of the class described, in combination, valve casings, valve stems projecting from said valve casings and rotatable, lever handles rigidly mounted on said valve stems, each having one section thereof 100

substantially circular in cross section, a lug having a vertical orifice therethrough mounted on the circular section of one of said lever handles, a lug having a vertical orifice therethrough and mounted on the circular section of the other lever handle, a rod rigidly secured to one of said lugs and adjustably secured to the other of said lugs

and having a handle at the lower end thereof.

Signed at the city of Montreal, Quebec, Canada, this thirteenth day of May, 1913.

JOSEPH ROBERT GIBSON.
